DESIGN FOR A JUVENILE VEHICLE

Michael E. Berry, Toledo, Ohio, assignor to The American-National Company, Toledo, Ohio, a corporation of Ohio

Application May 26, 1937, Serial No. 69,570

Term of patent 7 years

To all whom it may concern:

Be it known that I, Michael E. Berry, a citizen of the United States of America, residing at Toledo, in the county of Lucas, in the State of Ohio, have invented a new, original, and ornamental Design for a Juvenile Vehicle, of which the following is a specification, reference being had therein to the accompanying drawing, forming a part thereof, wherein:

I claim:

The ornamental design for a juvenile vehicle substantially as shown.

MICHAEL E. BERRY.
